CLAIM

The ornamental design for a food package with surface indicia, as shown and described.

DESCRIPTION

FIG. 1 is a front elevation view of a food package with surface indicia in accordance with a first embodiment of my new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front elevation view of a food package with surface indicia in accordance with a second embodiment of my new design;

FIG. 8 is a rear elevation view thereof;

FIG. 9 is a left side elevation view thereof;

FIG. 10 is a right side elevation view thereof;

FIG. 11 is a bottom plan view thereof; and,

FIG. 12 is a top plan view thereof.

The claim is directed to only the solid line features of the food package. All other features of the food package are not part of the claimed design. The evenly broken lines are shown for the purpose of illustrating parts of the article that form no part of the claimed design.
